UNITED STATES PATENT OFFICE.

FRIEDRICH KELLER, OF MILWAUKEE, WISCONSIN.

INSIDE BLIND, &c.

SPECIFICATION forming part of Letters Patent No. 317,798, dated May 12, 1885.

Application filed September 26, 1884. (No model.)

To all whom it may concern:

Be it known that I, FRIEDRICH KELLER, of Milwaukee, in the county of Milwaukee, and in the State of Wisconsin, have invented 5 certain new and useful Improvements in Inside Blinds, &c.; and I do hereby declare that the following is a full, clear, and exact description thereof.

My invention relates to window blinds or to shutters, and has especial reference to the slats of such as are known as "inside" blinds; and it consists in certain peculiarities of construction, as will be more fully set forth hereinafter.

In the drawings, Figure 1 is a side elevation 15 of a window blind or shutter provided with my improved devices. Fig. 2 is a horizontal section thereof; and Fig. 3 is a vertical section, but showing only four slats to avoid confusion of details.

20 C C represent the blind-stiles, C' the top rail, and C² the bottom rail, of the blinds, and c c represent my improved slats. The upper lap, c', of said slats is made slightly shorter than the lower lap, c², the outer beveled edges 25 of the blind-stiles C C being correspondingly projected inward or toward each other, as shown at c' c². This is done to secure a longer bearing for the tenons c⁴ of the slats and to reinforce them, and also to more effectually shut 30 out the light when the slats are closed, the lower lap, c², of one slat being thus made to overreach the upper lap ends of the adjacent slat when they are closed. The closing-bar of the slats consists of a single piece, c⁶, of the 35 shape shown in Fig. 3, and this strip or bar is fastened to one end of each of the slats at the edge of their lower laps, c², by means of screws or nails c⁵, part of the inner surface of the said bar c⁶ being sawed out or removed between 40 each two slats, to allow of the free play of said closing-bar and of its fastening-screw or nail-heads between said ends of the slats and the adjacent edge of the panel-stile, which is beveled away, as shown at c', to further assist in 45 this result, the other stile being likewise beveled away similarly for the sake of uniformity of appearance.

In order to form a close joint and exclude 50 the light between the upper edge of the upper slat and the lower edge of the upper rail, C', the outer beveled edge of the said upper rail

is at a more obtuse angle or higher up than the inner beveled edge, c⁸, forming a shoulder, c⁹; and hence, when the slats are closed, the upper lap, c', of the top slat will rest against 55 said shoulder c⁹, effectually excluding the light at top, as shown by the dotted lines in Fig. 3, and, similarly, the inner beveled edge of the lower rail, C², is made at a more obtuse angle or lower down than the outer beveled edge, 60 c¹⁰, of said lower rail, thereby forming a corresponding shoulder, c¹¹, against which the lower lap, c², of the lowest slat rests when all the slats are closed, thereby intercepting the light 65 at this point, as likewise shown by the dotted lines in Fig. 3. Thus in my improved window-blinds I am enabled to everywhere effectually shut out the light, when required, above and below the series of slats, as well as at each side thereof, besides providing a receptacle 70 for the closing-bar c⁶ at one side of the slats, so that the innermost projecting points of the closed slats and closing-bar will be flush with each other—a feature of importance, especially 75 when my improved blinds are used in connection with the sliding devices covered by my application for a patent for improvements in inside blinds filed May 19, 1884. The slats c c are perfectly flat on both sides and of the same diameter throughout in cross-section, 80 (except at the edges of their laps, where they are slightly rounded, as shown,) and in case one of the slats should become broken its place could be readily supplied by another, inasmuch as the nails or screws c⁵ are all removable, and the edge of the lap c² of the slat 85 against which the bar c⁶ is placed is perfectly flat and smooth, without any projections whatever, which would otherwise interfere with the ready removal of a broken slat and the 90 substitution of a new one; and this I deem a valuable feature of my present improvement.

I have described my invention with especial reference to inside blinds; but it is equally applicable to outside window-shutters.

95 Wherever I have used the terms "inner" and "outer" it is with reference to the location of the blinds in use—that is, "outer" is next to the window or next to outdoors, and "inner" is the side next the room or other 100 apartment where the blinds are located when the blinds are closed.

I am aware of the patents granted to J. and W. F. Behel on July 11, 1876, and G. W. Morstatt on March 18, 1879, for improvements in window blinds or shutters, one showing a slat 5 with laps and the other a closing-bar analogous to those elements in my device, and I disclaim the said several elements individually; but,

Having thus described my invention, what 10 I claim as new, and desire to secure by Letters Patent, is—

In window-blinds, the combination of the stiles C C, having overlapping outer beveled edges, c^3 , and inner shorter beveled edges, c^1 ,

with the flat slats c^2 , having short laps c^4 and 15 longer laps c^5 , and tenons c^6 , and the closing-bar c^7 , secured by removable nails or screws c^8 to and against the perfectly flat and smooth end edges of the laps c^5 at one side of the slats, substantially as set forth.

In testimony that I claim the foregoing I have hereunto set my hand, at Milwaukee, in the county of Milwaukee and State of Wisconsin, in the presence of two witnesses.

FRIEDRICH KELLER.
